[57] CLAIM

The ornamental design for a high rise faucet with pull-out spray, as shown and described.

DESCRIPTION

FIG. 1 is a top, front perspective view of a high rise pull-out spout faucet showing my new design;

FIG. 2 is a front elevational view thereof;

FIG. 3 is a top plan view thereof;

FIG. 4 is a right side elevational view thereof, the left side being a mirror image;

FIG. 5 is a rear elevational view thereof; and,

FIG. 6 is a bottom plan view thereof.

The broken line showing of the aerator in FIGS. 2, 4 and 6, and of the spray apertures in the faceplate in FIGS. 2, 4 and 6 are for purposes of illustration only and form no part of the claimed design.
